CLAIM

The ornamental design for a package for personal care items as shown and described.

DESCRIPTION

FIG. 1 is a front perspective view of our new package for personal care items design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is an exploded front perspective view thereof.

The broken dash lines shown in the drawing views illustrate portions of the package for personal care items as well as environmental structure. All broken lines in the drawings form no part of the claimed design.

1 Claim, 8 Drawing Sheets
